DESIGN FOR A DISPENSER FOR CUPS OR THE LIKE

Paul A. Lobel, New York, N. Y., assignor to Herz
Cup Company, Incorporated, New York, N. Y.,
a corporation of New York

Application July 8, 1933. Serial No. 48,662

Term of patent 14 years

To all whom it may concern:

Be it known that I, PAUL A. LOBEL, a citizen of the United States, residing at New York, in the county of Bronx and State of New York, have invented a new, original, and ornamental Design for a Dispenser for Cups or the like, of which the following is a specification, reference being had to the accompanying drawing, forming part thereof.

The single figure of the drawing is a perspective view of a cup dispenser showing my new design.

According to my design, the metallic sleeve-like conduit through which the cups are dispensed carries near its upper end a plurality of annulets or rings standing out slightly from the surface of the conduit and near but spaced from its lower end another series of annulets or rings standing out a substantial distance from the surface of the conduit. Within each series the rings are of uniform diameter. The upper ring of the first mentioned series carries integrally on its

upper flat surface a thin extension of less diameter than said upper ring, and adapted to abut the surface of the cylindrical glass container, while the upper and lower rings of the second or lower series carry integrally on their outer surfaces a thin extension of less diameter than said rings.

The outer surfaces of all the annular rings and of the visible portions of the sleeve or conduit are bright, smooth and highly polished, except that the surfaces between the rings of each series, while also bright, have a roughened or stippled surface.

The hook shaped element upon which the cups fall as they are released from the conduit carries at its end an elongated bead.

I claim:

The ornamental design for a dispenser for cups or the like, as shown and described.

PAUL A. LOBEL.
